UNITED STATES PATENT OFFICE.

MERTON C. GREEN, OF WILLIAMSPORT, PENNSYLVANIA.

BURNER.

1,283,157.

Specification of Letters Patent.

Patented Oct. 29, 1918.

Application filed June 7, 1917. Serial No. 173,286.

To all whom it may concern:

Be it known that I, MERTON C. GREEN, a citizen of the United States, residing in Williamsport, Pennsylvania, in the county 5 of Lycoming and State of Pennsylvania, have invented certain new and useful Improvements in Burners, of which the following is a specification.

The invention relates to improvements in 10 burners using illuminating, manufactured or producer gas as fuel, which is mixed with air under compression delivered by any suitable means, the device operating broadly under the principle of the well known Bunsen burner.

The structure of the device stated broadly, comprises two chambers, one of which communicates with a source of fuel supply and the other chamber with a source of air under 20 pressure, in combination with a nozzle formed on one chamber which is in communication with the other chamber; the chambers and nozzle or outlet orifice so arranged that the fuel and air under compression are 25 not permitted to intermingle until they reach the outlet orifice. Due to the particular arrangement of the chambers and the construction of the nozzle, the air supplied to the nozzle at great velocity is expanded 30 and reflected back upon itself to a focal point varying in position depending upon the amount of fuel and velocity of the air supply. This expansion of the air causes a 35 reduction of the gas flow, but permits the air to absorb and to be impregnated with the fuel thereby governing the mixture of air and gas automatically through a wide range of flame adjustment. This restriction or choking of the gas by the velocity 40 of the air tends to cushion the outflowing charge, produces an evenly mixed combustible charge, thus maintaining a perfect mixture. Under correctly proportioned pressures of gas and air, the amount of gas consumed is governed by the velocity and the 45 quantity of air leaving the burner and by such restriction the gas cannot pass out of the burner without first thoroughly combining with the moving air, the gas being 50 so controlled by such action that only enough passes out to combine properly with the air, thereby governing the amount of

fuel used through a very wide range of flame sizes, producing automatically one temperature throughout said flame range. 55

Burners constructed in accordance with the inventions are especially suitable for brazing, and preheating castings preparatory to oxy-acetylene welding of steel, cast iron, copper, bronze, aluminum, etc. They may 60 also be used for melting tin, solder, lead, zinc, babbitt, aluminum, brass, bronze, copper, and for drying cores, heating coke ovens, metal stampings, annealing, tempering and heat treating furnaces, lighting 65 cupolas, dry molds and ladles, starting fires under steam boilers, and a variety of other uses where intense heat is required.

Other objects, advantages and uses, will be set forth in detail in the following description and drawings which illustrate one embodiment of the invention and in which, 70

Figure 1 is a side elevation of the improved burner.

Fig. 2 is an enlarged vertical sectional view. 75

Fig. 3 is an enlarged side elevation having a portion of one chamber broken away and showing the interior chamber in elevation. 80

Fig. 4 is a diagrammatic view illustrating the action of the fuel and air within the burner.

The burner as illustrated in the drawings herewith may be made in accordance with 85 general engineering practice, that is, it may be made up of various sizes of tubing welded together, or of sheet drawn metal parts welded together, or it may either be cast, and I do not desire to be restricted to 90 the exact method of assembly of the burner as the invention herein resides in the structure and not its mode of development.

Referring now to the drawings in detail in which like reference numerals designate 95 similar parts throughout the several figures:

The improved burner comprises a casing 1, having one end reduced as at 2, which may be screw threaded as at 3. A second or interior casing 4 is arranged within the casing 1 and is joined to the rear end of the casing 1 as at 5 which, in the present instance, is shown as being secured to the periphery of the casing adjacent the point 100

of connection 2. The interior casing 4 may be reduced at 6 to form a nozzle portion 7. The end of the casing 1 opposite to that carrying the nipple 3 is provided with a blunt nose 8 to the edge of which is secured an inwardly projecting deflector nozzle 9, which forms the mixing and combustion chamber. The member 9 is of a larger diameter than, and extends inwardly a distance sufficient to surround, the end of the nozzle 7 to which it may be secured, as in the present instance, by means of arms 10 providing means for holding the nozzle and tubular member 9 in correct alinement and relation.

The periphery of the casing 1 adjacent the point of connection 2 is provided with an externally screw threaded nipple 11 secured thereto.

From the above it is apparent that the burner construction comprises two concentrically arranged chambers, the exterior and interior casings forming such chambers having individual inlet portions, their exhaust ends being concentric, overlapping, and ending in a common exhaust section which forms an ignition chamber, all of such casings and ports being rigidly fixed in their critical relative positions.

In operating the burner, air under pressure is supplied through connection 3, passing through the interior casing 4 and is discharged from the nozzle 7 at high velocity. The air on leaving the end of the said nozzle expands in cone shape as is shown by dotted lines in Figs. 2 and 4, and is then reflected back to some focus 9', by the wall of the tube 9, thus forming a somewhat stiff cushioning screen of air against which the fuel gas is pressed and into which the fuel gas is absorbed. This expansion and reflection being due, first, to the differences in diameter of the nozzle and tube; and second, to the high velocity of the air. Fuel is supplied to the casing 1 through the connection 11 and moves through the chamber as is indicated by the arrows 1'. Due to the expansion of the air within the pipe 9 the fuel is cushioned, so to speak, against the air and within the space between the casing 1 and the outer periphery of the pipe 9 as is illustrated by the arrows 1', Figs. 2 and 4. This cushioning of the fuel causes an even distribution of fuel and air at its point of mixture 10' within the tubular member 9, whereby a perfect and uniform combustible mixture is provided which insures a flame balanced throughout its cross sectional area.

The expansion of the air and the restriction of the fuel flow, as above described, causes a syphoning action on the fuel, the air drawing a sufficient amount of fuel with it in its passage through the mixing chamber 9, the fuel drawn out being taken from

the cushion of fuel existing in the rear of the point of expansion of the air. Due to this arrangement the air supply causes an automatic regulation for the amount of fuel mixed therewith.

The distance the nozzle member 7 enters into the tube 9 is a predetermined amount and is usually fixed, or permanently set and is therefore non-adjustable. Under the proportioned gas and air mixtures the temperature of the flame formed thereby may be kept substantially constant within wide ranges of flame sizes. It has been found that changing the critical relation of the orifices of the tubes 7 and 9 causes poor mixture and therefore a great reduction of flame temperatures.

A further reason for fixing these tubes is that finding and fixing the critical relative position permits of a high temperature being obtained by a gas and air mixture at low air velocity, and allowing the ignition point of the gas to remain inside of the burner tube 9. It is obvious that when a combustion has been started within the tube 9, externally induced air currents at atmospheric pressures cannot enter and weaken the mixture sufficiently to cause the mixture velocity to overcome the flame velocity or flame propagation.

Another feature in having the relations of the burner tube 9 and the air tube 7 relatively set to one another, is that aside from obtaining, automatically, the proper mixtures which are readily combustible at low air velocities, I obviate the possibility of incompetent manual adjustment of the flame, thereby fixing the economy and efficiency of my device.

It will therefore be seen from the foregoing that by my construction I am able by means of the fixed air and burner tubes and the related throttle orifice therebetween to not only sufficiently regulate that proper mixture of the gases, but also to maintain the point or beginning of combustion within the burner tube 9; or, in other words, to regulate the point of union of the combustible gases with a predetermined amount of air at a position protected from stray or accidental air currents thereby producing a readily combustible mixture at a low air velocity and capable of producing at such low velocity much higher temperatures at a greater fuel economy.

I have also found in tests that my burner attains temperatures not, to my knowledge, claimed of any other burners of this class showing that the principle of fixed conducting tubes of certain related diameters, as previously described, prove entirely satisfactory in practice.

Due to the reflection of the air and fuel mixture by the walls of the mixing chamber 9, this mixture focalizes at some point in

front of the burner, the distance varying according to the amount of gas and the velocity of the air supplied the burner.

Since, in applicant's burner the flow of fuel is limited to that which is properly taken up by the air, his burner is odorless when in use, thus showing that the combustion is complete.

Any suitable means for compressing the air may be used and as any one of a variety of means may be employed, no mechanism *per se* is illustrated.

The orifice, *i. e.*, the outer end of the tubular member, may be shaped other than circular when desired, producing special shaped flames without varying the quality and intensity thereof.

Burners heretofore known to applicant for welding and other purposes where intense heat is required have only been able to develop a flame having a temperature of 2400° Fahrenheit, the burners referred to using gasolene or kerosene as fuel, or burners known as gas-air burners. Burners made in accordance with this invention, however, generate 3500° Fahrenheit as their maximum temperature, which accomplishes the result, that work may be completed in a shorter time and that a saving of about one-third of the cost of fuels required by the other burners herein mentioned. As the other burners approach their maximum of 2400° Fahrenheit, they burn a large amount of fuel, whereas burners made in accordance with my invention, when developing an equivalent heat, use only approximately three-quarters of the amount of fuel used heretofore. In addition where temperatures are required which exceed 2400° Fahrenheit, burners made in accordance with this invention will develop temperatures beyond the range of other types of burners. As an example, burners made according to my construction, will melt cast iron, steel, Hessian sand crucibles, porcelain, asbestos mill board, and will reduce the size of the small bits of platinum iridium which will not gasify until they reach a temperature considerably above 3000° Fahrenheit.

I claim:

1. In a burner, the combination of an inner tubular casing having a substantially unrestricted and unobstructed open outer end; an outer casing surrounding the inner casing; and a deflector nozzle receiving a portion of the inner casing and having gas-tight connection with the outer casing.

2. In a burner, the combination of an inner tubular casing having an outer end portion; an outer tubular casing surrounding the inner casing; means for feeding gas to said casings respectively; and a cylindrical tubular deflector nozzle co-axial with said outer end portion and slightly larger in diameter than said outer end portion and

receiving the outer end portion, said nozzle having a length more than twice its diameter.

3. In a burner, the combination of an inner tubular casing having an outer end portion; an outer tubular casing surrounding the inner casing co-axial therewith and having an inwardly curved free end portion; means for feeding gas to said casings respectively; and a tubular deflector nozzle co-axial with said outer end portion and slightly larger in diameter than said outer end portion and receiving the outer end portion, said nozzle having a length more than twice its diameter, and a gas tight connection at its outer end with the free end portion of the outer casing.

4. In a burner, the combination of an inner tubular casing having a straight cylindrical reduced outer end portion of constant diameter and of a length equal to more than four times its diameter; an outer tubular casing surrounding the inner casing coaxial therewith and having an inwardly curved free end portion; means for feeding gas to said casings respectively; and a cylindrical tubular deflector nozzle co-axial with said outer end portion and slightly larger in diameter than said outer end portion and receiving the outer end portion, said nozzle having a length more than twice its diameter, and a gas-tight connection at its outer end with the free end portion of the outer casing.

5. In a burner, the combination of an inner tubular casing having an outer end portion of constant diameter about four times the length of such diameter; an outer tubular casing surrounding said inner casing; and a tubular deflector nozzle of substantially constant diameter slightly larger than the diameter of and receiving a short portion of said outer end portion, and having a length greater than its own diameter and having, at its outer end, gas-tight connection with said outer casing.

6. In a burner, the combination of an inner tubular casing having a straight cylindrical reduced outer end portion having a length equal to about four times its diameter; an outer tubular casing surrounding the inner casing co-axial therewith and having an inwardly curved outer end; means for feeding gases to said casings respectively; and a cylindrical tubular deflector nozzle co-axial with and slightly larger in diameter than and receiving a short portion of the outer end of said reduced portion and having a gas-tight connection at its outer end with said inwardly curved portion, and having a length slightly more than twice its own diameter, said reduced portion and said nozzle being free of obstructions.

7. In a burner, the combination of an inner tubular casing having a straight cylin-

cylindrical reduced outer end portion about four times the length of its diameter; an outer tubular casing surrounding the inner casing co-axial therewith and having an inwardly curved outer end; means for feeding different gases to said casings respectively; and a cylindrical tubular deflector nozzle having a diameter approximately twice the diameter of said reduced end portion and dis-

posed co-axial with and receiving a small portion of said reduced portion, said nozzle having a gas-tight connection with the outer end of said curved end and having a length slightly more than twice its own diameter.
